GAME CHIP

Joseph H. Garaventa, Reno, Nev., assignor to
Harrah's Club, Reno, Nev.

Original design application Mar. 20, 1972, Ser. No.
236,540. Divided and this application Feb. 19,
1974, Ser. No. 429,040

Term of patent 14 years

Int. Cl. D12—01

U.S. Cl. D34—5 GP

FIG. 1.

FIG. 2.

FIG. 3.

FIG. 4.

FIG. 1 is a perspective view of a game chip showing my new design;

FIG. 2 is a plan view thereof;

FIG. 3 is a side elevational view thereof; and

FIG. 4 is a front elevational view thereof.

This application is a division of my co-pending application Ser. No. D. 236,540, filed Mar. 20, 1972 for Design for Game Chip.

I claim:

The ornamental design for a game chip, as shown and described.
